UNITED STATES PATENT OFFICE

132,725

DESIGN FOR A CLOTHING RACK

Theodore Sokolove, Baltimore, Md.

Application November 5, 1941, Serial No. 104,032

Term of patent 7 years

To all whom it may concern:

Be it known that I, Theodore Sokolove, a citizen of the United States, residing at Baltimore City, in the State of Maryland, have invented a new, original, and ornamental Design for a Clothing Rack, of which the following is a specification, reference being had to the accompanying drawing, forming part thereof.

ing rack, showing my new design, the opposite side being substantially the same as the side illustrated; and

I claim:

The ornamental design for a clothing rack, as shown and described.

THEODORE SOKOLOVE.
